UNITED STATES PATENT OFFICE.

HENRY W. ROOUNTREE, OF RICHMOND, VIRGINIA, ASSIGNOR OF ONE-HALF
TO HENRY W. COTTRELL, OF RICHMOND, VIRGINIA.

TRUNK.

No. 851,033.

Specification of Letters Patent.

Patented April 23, 1907.

Application filed May 18, 1906. Serial No. 317,574.

To all whom it may concern:

Be it known that I, HENRY W. ROOUNTREE, a citizen of the United States, residing at Richmond, in the county of Henrico and State of Virginia, have invented certain new and useful Improvements in Trunks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to trunks, and more especially to that class of trunks known as "wardrobe-trunks," and has for its object the special construction of the wardrobe-section in order to permit individual garments or 20 suits of clothes to be hung on the hangers and said hangers hung on a frame capable of being projected out from the wardrobe-section for easy access to the clothes, and when the trunk is packed said frame can be pushed 25 back into the wardrobe-section, in combination with means for holding the clothes tightly in the section when the trunk is closed, together with details of construction hereinafter to be particularly pointed out in 30 the specification and claims.

Referring to the drawings, in which like parts are similarly designated, Figure 1 is a perspective view of the trunk in open position, and Fig. 2 is a vertical section of the trunk 35 in closed position.

In the particular style of trunk herein illustrated there are two sections, a wardrobe-section A and a bureau-section B, said bureau-section containing a suitable number 40 of drawers C, the top of the trunk when in perpendicular position being provided with the usual bulged or rounded portion D to prevent the trunk from being stood on that end.

In the wardrobe-section I provide a suitable frame E, here shown as a rectangular metallic open frame, having a central rod F, extending from the front to the back of the frame and on which clothes-hangers are to be hung. Slots E' or equivalent devices 50 are formed on the frame and act as handles by which the frame may be moved to the desired position. This frame has two links G and H at each side thereof. The upper ends of the links are pivoted to the frame at I and

K and the lower ends to the wardrobe-section at L and M, and preferably to the plate N, secured to the sides of the wardrobe-section, so that these links, with the frame, form a parallel motion whereby said frame may be drawn from within the wardrobe-section, 55 maintaining its horizontal position and held firmly thereby in a like position projecting from said section. One of the links at each side of the frame is limited in its outward movement by a stop, which I preferably 60 form, as a slotted guide O, securely holding the frame in proper relation to the wardrobe-section when in extended position.

The wardrobe-section is provided with a closure P, hinged to one edge thereof, preferably to the edge opposite the one to which the section B is hinged, and operating as a door, said door having on its inside a compressing member adapted to compress the garments hung on hangers on the frame to 70 maintain said garments in compact extended position when the trunk is closed independent of the thickness or the number of garments in the wardrobe-section and to prevent the garments from being tumbled into one 75 end of the section during the transportation of the trunk. This compressor consists of the follower or member R, secured to a bow-spring S, secured at one end by hinge T to door P, the other end being formed to slide 80 on a wear-plate U, secured to the inner face of the door, said wear-plate preferably, but not necessarily, provided with lateral guide-ribs U'. The spring S is bowed, so that when it is compressed by closing the door the follower R, which is preferably secured at its center to the bowed spring, will have universal movement during compression, thereby 85 permitting it to accommodate itself to various thicknesses in the wardrobe-section. The door is provided with suitable fastening devices or latches V to hold it in a closed position.

The operation is as follows: The frame E, being in the position shown in the drawings, 90 is grasped through the slots E' and shoved back into the section. The closure or door P is then shut. The compressing member R engaging the clothes below the frame and hangers thereon forces and compresses them tightly 95 into the section. By reason of the bowed spring S the member R, which is only secured to the spring S at the center, can have a uni-

versal movement, one edge engaging and commencing to compress the clothes, the compressing increasing as the door continues the closing action. The door is then fastened by the latches V, and the clothes in the wardrobe-section will be held by the action of the spring S on the member R. The lower end of said spring S bears on the wear-plate U.

I claim—

10. 1. The combination with a wardrobe-section; of a frame in the upper part of said section and means to support the frame in the section and permit it to be extended therefrom, a hinged closure for the section and a yielding compressor on the closure below the frame.

15. 2. The combination with a wardrobe-section; of a closure for the section, and a yielding compressor hinged to the closure, substantially as described.

20. 3. In a trunk, the combination with a wardrobe-section, and a second section hinged to one side of said wardrobe-section; of a door hinged to the other side of said section and a compressing member on the door, substantially as and for the purpose set forth.

25. 4. In a trunk, the combination with a wardrobe-section; of a clothes-supporting frame therein, means to movably support the frame in the section and permit it to be drawn forward from the section when the trunk is open, a door hinged to one side of said section, a yielding compressor on the door to engage the clothes below the frame when the door is closed and a second trunk-section hinged to the other side of the wardrobe-section, substantially as described.

5. The combination with a wardrobe-section; of a closure therefor, a bow-spring hinged at one end to the closure, a wear-plate 40 on the closure on which the other free end of said spring slides, means to prevent the lateral displacement of said free end of the spring and a compressor mounted on the spring, substantially as and for the purposes 45 set forth.

6. In a trunk, the combination with a wardrobe-section; of a flat metal rectangular frame having hand-holes in its front wall, a clothes - hanger - supporting rod extending 50 across the frame, a pair of flat metal links at each side of the frame pivotally connected at their upper ends to the frame and at their lower ends pivotally connected to the side walls of the wardrobe-section near their top 55 and limiting means secured to the side walls of the section against which the rear link of each pair abuts when the frame is extended from the section.

7. In a trunk, the combination with a 60 wardrobe-section, and a closure therefor; of a spring member hinged to the closure and a compressing member mounted on the spring member, said spring member permitting the compressing member to have universal 65 movement.

In testimony that I claim the foregoing as my invention I have signed my name in presence of two subscribing witnesses.

HENRY W. ROUNTREE.
